UNITED STATES PATENT OFFICE.

CHARLES ED. HAVILAND, OF LIMOGES, FRANCE.

DESIGN FOR A DISH.

SPECIFICATION forming part of Design No. 19,273, dated August 20, 1889.

Application filed January 5, 1889. Serial No. 295,569. Term of patent 14 years.

To all whom it may concern:

Be it known that I, CHARLES EDWARD HAVILAND, a citizen of the United States, residing at Limoges, Republic of France, have 5 invented and produced a certain new and original Design for Dishes, fully described and represented in the following specification and the accompanying illustration, forming a part of the same.

- 10 In the accompanying illustration, Figure 1 is an end view of a covered dish embodying the design, and Fig. 2 a perspective view of the same.

The following are the leading features of 15 the design: The sides *a* and ends *b* of the dish-body are plain, substantially parallel. The corners of the body are rounded and are corrugated vertically, so as to give the upper edge of the dish-body a scalloped form at the 20 corners. The central corrugations 2 at the corners swell outward from the top to the base of the body, while the adjacent corrugations 3 swell outward at the top of the body, but are reversed as they approach the bottom 25 and form depressions at their junction with the base, as shown at 4.

The cover is slightly dome-shaped, and in 30 outline corresponds substantially to the outline of the top of the dish-body, its sides *c* and ends *d* being substantially parallel and its corners rounded and scalloped. The corners of the cover, like the corners of the body, are corrugated, the corrugations converging toward and vanishing as they approach the center of the cover. The corrugations upon the 35

cover correspond with the scallops at its corners, and are alternately convex and concave, as indicated at 5 and 6, respectively. The cover is provided with a handle *f* in the form of a knob, representing a conventional bud 40 or flower or vegetable growth, the stem of which unites with the cover, and is bent so as to lie upon the top of the cover more or less in relief, it being represented as extending beneath a band or scroll 8, also more or less 45 in relief. The dish-body may also be provided with handles *g*, and these handles, when provided, are of scroll form, the ends of the scroll uniting with the dish-body and the central portion of the scroll curving outward and 50 upward.

What I claim is—

1. The design for a covered dish, substantially as herein shown and described, the same comprising the body and cover. 55
2. In a design for a dish, the design for the cover, substantially as herein shown and described.
3. In a design for a dish, the design for the body, substantially as herein shown and described. 60

In testimony whereof I have hereunto set my hand in the presence of two subscribing witnesses.

CH. ED. HAVILAND. [L. S.]
